UNITED STATES PATENT OFFICE.

HARRY F. ZIMMERLIN AND CHARLES G. ZIMMERLIN, OF LYONS, NEW YORK.

AX-RACK.

SPECIFICATION forming part of Letters Patent No. 553,445, dated January 21, 1896.

Application filed April 29, 1895. Serial No. 547,483. (No model.)

To all whom it may concern:

Be it known that we, HARRY F. ZIMMERLIN and CHARLES G. ZIMMERLIN, of Lyons, in the county of Wayne, in the State of New York, have invented new and useful Improvements 5 in Ax-Racks, of which the following, taken in connection with the accompanying drawings, is a full, clear, and exact description.

The object of this invention is to display 10 in stores samples of chopping-axes in such a manner as to hold them in a compact and neat position and without danger of injuring persons approaching the display apparatus, and also permit the axes to be easily applied 15 and removed from the apparatus; and to that end the invention consists in the novel construction and combination of the component parts of the display-rack, as hereinafter described, and set forth in the claims.

20 In the annexed drawings, Figure 1 is an elevation of a display apparatus embodying our invention. Figs. 2 and 3 are enlarged plan views of portions of the ax-supporting plates, and Figs. 4 and 5 are transverse sections, respectively, on lines XX and YY in 25 Figs. 2 and 3.

A represents the standard or support of the display-rack, which support may be of any suitable shape. Upon the top of the 30 standard is firmly secured the horizontal plate P, preferably of annular shape. The plate is formed with horizontal radially-projecting brackets a a, each of which terminates with the lateral offset a' on its free end, between 35 the end of which offset and adjacent bracket a is a space c, which serves as a passage to the recess b, formed between the brackets by the aforesaid offset, as shown in Fig. 2 of the drawings. Each of the brackets is provided with an upward-projecting lug d on 40 the free end of the offset a', and also preferably with a rib d' on top of said offset. The top of the plate p is provided with ribs l l. The purpose of this plate is to carry a plurality of axes attached to handles. Said axes are mounted on the described display-rack by placing the ax with its handle depending therefrom and passing the handle laterally through the space c, then moving the ax lat-

erally to carry the handle thereof into the recess b, and then setting the back of the ax onto the rib d and placing the front portion of the ax between the ribs l l on the plate, said ribs and the lug d serving to retain the ax on the bracket. 50

To provide lateral supports for the depending handles of the axes, we attach to the lower portion of the standard A a horizontal plate C, against the edge of which said handles rest, as shown in Fig. 1 of the drawings. 55

For displaying axes detached from the handles we provide the top of the plate C with ribs h h and spurs i i, which latter enter the eyes of the axes set upon the aforesaid ribs, as illustrated in Figs. 3 and 5 of the drawings. 60

What we claim as our invention is—

1. The within described ax-rack consisting of the standard —A—, an annular horizontal plate —P— secured upon said standard and 70 formed with horizontal radially-projecting brackets —a—a— each terminating with a lateral offset —a'— on the free end forming a recess —b— between the brackets to receive the suspended handle of the ax supported on the 75 bracket, and a passage —c— to said recess, a lug —d— on the free end of each offset, a rib —d'— on top of each offset to support the back of the head of the ax, ribs —l— on top of the plate —P— between which the front 80 portion of the head of the ax is held, a horizontal plate —C— secured to the lower portion of the standard —A— for the depending handles of the axes supported on the brackets —a—a— of the plate —P— to rest against, ribs —h— 85 formed on the plate —C— for supporting axes detached from the handles, and with spurs —i— entering the eyes of said axes as set forth and shown.

2. In a display rack for axes, the combination of the standard —A—, an annular horizontal plate —P— secured upon the top thereof and formed with horizontal radially-projecting brackets —a—a— each terminating with a lateral offset —a'— on its free end forming 90 the recess —b— between the brackets to receive the suspended handle of the ax held on the bracket and a passage —c— to said recess, 95

a lug — *d* — on the free end of the offset — *a'* —, a rib — *d'* — on top of the offset of each bracket to support the back of the ax, and ribs — *l* — *l* — of said plate — between which the front portion of the ax is held as set forth and shown.

5 3. In combination with the standard, the plate — *C* — provided with ribs — *h* — *h* — for supporting the heads of the axes, and with spurs — *i* — *i* — entering the eyes of the axes

mounted erect on the aforesaid plate substantially as described and shown.

In testimony whereof we have hereunto signed our names this 20th day of April, 1895.

HARRY F. ZIMMERLIN. [L.S.]

CHARLES G. ZIMMERLIN. [L.S.]
